CHARCOAL LIGHTER

Lester D. Drugmand, Pittsburgh, Pa., assignor to Edwin L. Wiegand Company, Pittsburgh, Pa.

Filed Nov. 22, 1960, Ser. No. 62,928

Term of patent 14 years

(Cl. D81—10)

I claim:

The ornamental design for a charcoal lighter, substantially as shown.
